UNITED STATES PATENT OFFICE.

FRIEDRICH WILHELM JURGSCHAT, OF HUFEN, GERMANY.

LIFE-PRESERVER.

SPECIFICATION forming part of Letters Patent No. 637,872, dated November 28, 1899.

Application filed July 21, 1899. Serial No. 724,719. (No model.)

To all whom it may concern:

Be it known that I, FRIEDRICH WILHELM JURGSCHAT, a subject of the German Emperor, residing at 15 Bahnstrasse, Hufen, near 5 Königsberg, Prussia, Germany, have invented certain new and useful Improvements in Life-Belts; and I do hereby declare the following to be a full, clear, and exact description of the invention, such as will enable others skilled in the art to which it appertains to make and use the same.

This invention relates to a life-belt with a number of flat metal shells connected together by straps or belts, which shells are filled with 15 elastic shells wherein smaller closed receptacles made of elastic material are placed. By means of this arrangement a much greater security is obtained than is possible with the known life-belts with single metal shells—20 such, for example, as those described in the United States Patent Specification No. 436,318 and the British Patents Nos. 5,710 and 14,061 of 1887—since the carrying or supporting power of the elastic shells and receptacles 25 contained therein is not interfered with by damage to one of the metal shells.

In the accompanying drawings a life-belt of this kind is shown extended in Figures 1 and 2, in outside and inside elevation, respectively. Fig. 3 shows a transverse section through the extended life-belt. Fig. 4 shows the life-belt fastened to the body. Fig. 5 shows one of the metal shells in elevation. Fig. 6 is a vertical section; Fig. 7, a vertical 35 transverse section taken on line $x-x$ of Fig. 6, and Fig. 8 a horizontal section taken on line $z-z$ of said Fig. 6.

The life-belt consists, essentially, of a number of flat metal shells A, which are connected 40 together by straps or belts. In the arrangement shown in Figs. 1 and 2 the metal shells A are placed in separate pockets. They can, however, be also secured directly to the connecting straps or belts.

45 The flat metal shells A, fitting the curvature of the body, are provided with an opening D for inserting long shells B, which are made of elastic material and are filled with smaller cylindrical, spherical, or otherwise 50 suitably formed receptacles C, which are likewise elastic. By reason of this arrangement

the carrying or supporting power of the life-belt is not materially interfered with if the metal shell A, or even one or other of the elastic shells B, should be damaged, since the 55 separate closed receptacles C have sufficient carrying or supporting power.

Having now described my invention, what I claim as new therein, and desire to secure by Letters Patent, is—

60 1. A life-preserver comprising a series of metallic cases, concavo-convex in horizontal section, and of less diameter than length and width, said cases united at one end by a waist-belt, and near the other by an encompassing strap, in combination with flexible cellular cases filling said metallic cases, for the purpose set forth.

65 2. A life-preserver comprising a series of metallic cases concavo-convex in horizontal section and of less diameter than length and width, those cases on a line with the armpits shorter than the others, said cases united at one end by a waist-belt and near the opposite end by an encompassing strap, in combination 70 with flexible cellular cases filling said metallic cases and having cells of different internal areas, for the purpose set forth.

75 3. A life-preserver comprising a series of metallic cases concavo-convex in horizontal section and of less diameter than length and width, a suitable pocket for each of said cases, a waist-belt uniting said cases at one end, and an encompassing strap uniting the same near their opposite end, those cases in line 80 with the armpits shorter than the others, in combination with flexible cases filling said metallic cases and filled with flexible cases forming air-chambers, for the purpose set forth.

85 90 4. A life-preserver comprising a series of metallic cases concavo-convex in horizontal section and of less diameter than length and width, a suitable pocket for each of said cases, a waist-belt uniting said cases at one end 95 and an encompassing strap uniting the same at their opposite end, those cases in line with the armpits shorter than the others, in combination with flexible cases filling said metallic cases, and filled with flexible cases forming air-chambers of different capacities, for the purpose set forth.

5. A life-preserved comprising a plurality of interconnected metallic shells each containing a plurality of flexible or elastic shells filled with closed cellular bodies, for the purpose set forth.

6. A life-preserved comprising a plurality of interconnected metallic shells each containing a plurality of flexible or elastic shells

filled with closed flexible or elastic cellular bodies, for the purpose set forth.

In testimony whereof I affix my signature in presence of two witnesses.

FRIEDRICH WILHELM JURGSCHAT.
